UNITED STATES PATENT OFFICE.

GEORGE WEISS, OF CHICAGO, ILLINOIS.

MACHINE FOR MAKING CEMENT DRAIN-TILES, &c.

1,142,864.

Specification of Letters Patent. Patented June 15, 1915.

Application filed September 23, 1911. Serial No. 650,971.

To all whom it may concern:

Be it known that I, GEORGE WEISS, a citizen of the United States, and a resident of Chicago, in the county of Cook and State 5 of Illinois, have invented certain new and useful Improvements in Machines for Making Cement Drain-Tiles, &c., of which the following is a full, clear, and exact specification.

10 My invention is concerned with a novel machine for making cement drain tile, and is designed to produce a machine of the class described which shall be simple in its construction, rapid in its operation, and which 15 shall be certain and accurate in use, and which shall be durable.

A special object of my invention is to produce a machine that shall lower the packer preparatory to making another tile 20 at a greater speed than it is raised in the operation of forming a tile, thereby increasing the possible output of a machine.

Another special object is to produce a mechanism for raising, lowering and rotating 25 the packer which will stop itself automatically when the packer reaches the limit of its upward or downward movement, thus stopping the movements both of rotation and translation.

30 Another special object is to produce a device of the class described, in which the adjacent bearing of the spindle will always be at the same distance from the packer which it supports, thereby increasing the 35 accuracy with which the packer is centered in the casing at all times, and consequently making the thickness of the tile more uniform at all points than has been possible heretofore.

40 To illustrate my invention, I annex hereto two sheets of drawings, in which the same reference characters are used to designate identical parts in all the figures, of which—

Figure 1 is a side elevation of the complete machine with a portion thereof in central vertical section, showing the parts in the position which they occupy just before the mechanism is automatically stopped at the end of the upward or forming movement 45 of the packing shaft; Fig. 2 is a similar view but with the parts in the position they assume just prior to the stopping of the machine automatically at the end of the downward movement of the packing shaft; Fig. 50 55 3 is a sectional view on the line A—A of Fig. 1; Fig. 4 is a front elevation of the gearing with the casing and the shifting

lever removed; and Fig. 5 is a detail in section on the line B—B of Fig. 1.

The various elements of the machine are 60 mounted in a suitably designed frame 10, which is preferably a single casting so as to give the necessary rigidity at all the parts and to prevent any possible displacement of the packer relative to the casing by reason 65 of the bearings becoming displaced.

The power is applied to a belt wheel or pulley 11, which is secured to the shaft 12, journaled in a suitable horizontal bearing 13 in the frame work and having secured on 70 the inner end thereof the beveled gear wheel 14, which where the machine is designed to lower the spindle carrying the packer at a greater speed than that at which it is raised, as is the preferred construction, has two sets of beveled gear teeth 15 and 16, the teeth 15 forming a beveled gear wheel of smaller diameter than that formed by the teeth 16. The teeth 15 mesh with a beveled gear pinion 17, journaled in a vertical bearing 18, formed in the frame work, and has on its upper surface a clutch member 19, while the teeth 16 mesh with a similar but oppositely disposed beveled gear wheel 20, journaled in the corresponding 85 bearing 21 and having the corresponding clutch member 22.

The packer shaft or spindle 23 has its upper portion screw threaded and engaging the stationary nut 24, secured in the bearing 25 as by the set screw 26, so that as the spindle 23 is rotated in either direction it will be raised or lowered as the case may be.

The spindle is journaled in the bearings formed by the hubs of the gear wheels 17 and 20 through which it passes and in which it is free to rotate, and it has a further bearing formed by the collar 27, which fits in the sleeve 28, which has secured thereto the cross-piece or spider 29, which supports the 100 hopper 30, secured on its lower end. This sleeve 28 has a certain amount of vertical movement, its upper end being guided in the bearing formed by the hollowed out hub of the gear wheel 17, while its lower portion is 105 guided in the bearing 31, carried by the frame work 10. A collar 32, clamped on the sleeve 28 limits its downward movement while its upward movement is limited by the engagement of its upper end with the 110 top of the hollow portion of the hub of the wheel 17. During its operation, the spindle 23 moves from an uppermost position, substantially that shown in Fig. 1, to a lower-

most position, substantially that shown in Fig. 2, and its lowermost bearing in all positions is formed by the engagement of the collar 27 with the interior of this sleeve 28, which thus forms an elongated bearing, in which the packer 33, secured on the lower end of the spindle, is always at the same distance from this bearing, and consequently is supported with the same certainty in all the position which the packer assumes in the customary casing 34, which when the machine is in operation is seated in the annulus 35, supported by the bracket 36, extending forward from the bottom of the frame 10. The spindle 23 is provided with a splined groove 37 throughout so much of its upper portion as is necessary to permit it to be secured by a spline to the sliding clutch member 38, which is provided on its upper and lower ends with the necessary teeth to engage with the clutch teeth 19 and 22 of the gear wheels 17 and 20 respectively. The member 38 also has the customary annular groove 39 engaged by the customary lugs on the forked end 40 of the bell crank lever 41 which serves as an operating lever to start or stop the machinery. In order to hold the lever in either one of its three positions, I provide suitable friction means, such for instance as is shown in Fig. 5, where it will be seen that the lever 41 has the comparatively large disk like surface 42, which engages the corresponding surface 43 on the bracket projecting from the inclosing casing 44. To increase the friction of these surfaces 42 and 43, I preferably hollow the hub 45 of the bearing bracket and locate therein the helically coiled expanding spring 46 which surrounds the bolt 47 and engages the washer 48, which is held against the end of the sleeve by the nut 49 and the lock nut 50, so that the desired degree of friction can be secured to insure the lever 41 always standing where it is left after it has been intentionally moved either automatically or by hand. To automatically stop the machine at the end of the upward movement of the spindle, I provide the rod 51 extending parallel thereto and mounted to slide in the bearings 52 and 53. The lower end of the rod 51 rests on the cross-piece or spider 29 when the latter is near the limit of its upward movement and at other times is supported by the collar 54 resting on top of the lug 52. The upper end at the end of the upward movement of the spindle engages the surface 55 carried by the forked arm of the lever 41, and thus disengages the clutch teeth and stops the upward movement of the spindle, the momentum of which will, of course, serve to carry the clutch teeth fully out of engagement before the rotation of the spindle stops. Similarly the downward movement of the spindle is automatically stopped by reason of the collar 56, secured

on the upper end thereof engaging the lug 57 on the slotted lever 58, pivoted on the frame and carrying at its free end the rod 59, which terminates above the surface 55, and consequently when the uppermost clutch members are engaged will serve to disengage them when the collar 56 strikes the lugs 57.

The operation of the complete device will now be readily apparent. When the spindle stops at the end of its downward movement, the annulus 59 of the packer extends down below the upper edge of the annular surface 60 of the supporting annulus 35, and the hopper 30 has been allowed to descend by gravity until its ring 61 rests on the top of the casing 34, which is thus firmly held. The cement is shoveled into the top of the hopper and falls down upon the packer so that when the handle 41 is swung to the proper position to start the rotation of the spindle to raise the packer, the packer lugs 62 will begin forcing the cement outward before the annular surface 59, which serves to smooth out and finish the interior of the tile, reaches the bottom of the tile. As the rotation of the shaft continues, the lugs 62 throw the cement outward and pack it against the inner surface of the casing 34, which inner surface is smoothed throughout its entire length by the annular surface 59 in the manner which will be readily understood. Toward the end of the upward movement of the spindle 23, the upper shoulder of the collar 27 engages the shoulder formed by the inwardly projecting flange 63 at the top of the sleeve 28 and the subsequent movement of the spindle 23 upward carries with it the sleeve 28 and consequently the hopper 30, which is thus lifted from the casing 34, which can now be removed and an empty one substituted. After the hopper has thus been disengaged from the casing, and as it moves upward with the spindle, its cross-piece 29 engages the bottom of the rod 51, and operates the clutch mechanism to disengage it and automatically stop the machine in the manner described. When an empty casing 34 has been put in place, the lever 41 is moved in the opposite direction to engage the uppermost clutch members in which arrangement the teeth 16 do the driving, and on account of the greater diameter of the beveled gear wheel where they are located, the spindle is rotated more rapidly, and consequently descends faster than it rises.

It will be apparent that the continued support of the spindle 23 at the same distance from the packer in all positions of the latter insures a more perfect centering of the spindle than would be possible otherwise, and this inures to the uniformity of the thickness of the tile throughout its length. It will also be noted that there is a considerable space between the exterior of

the spindle 23 and the interior of the sleeve 28, and this serves to prevent the cement, which may get on the spindle 23, from engaging this inner surface and thus destroying or wearing out the bearings more rapidly.

While I have shown and described my invention as embodied in the form which I at present consider best adapted to carry 10 out its purposes, it will be understood that it is capable of modifications, and that I do not desire to be limited in the interpretation of the following claims, except as may be necessitated by the state of the prior art.

15 What I claim as new, and desire to secure by Letters Patent of the United States, is:

1. In a device of the class described, the combination with a framework adapted to support a casing at a fixed point thereon, of 20 a packer spindle journaled in said framework, means for simultaneously rotating said packer spindle and moving it axially to and from the casing, said means acting at different points on the spindle as it is 25 moved axially, a bearing collar carried by the spindle at a fixed point thereon, and an elongated fixed bearing-sleeve within which the collar rotates and moves in all 30 positions of the spindle, thereby furnishing a bearing support for the spindle at the same distance from its free end in all positions thereof.

2. In a device of the class described, the combination with a frame work adapted to 35 support a casing at a fixed point thereon, of a packer spindle journaled in said frame work, means for simultaneously rotating said packer spindle and moving it to and from the casing, a bearing collar carried 40 by the spindle, an elongated bearing sleeve within which the collar rotates in all positions of the spindle, thereby furnishing a bearing support for the spindle at the same distance from its free end in all positions 45 thereof, a hopper carried by the lower end of the sleeve and adapted to fit on the top of the casing, and a shoulder in the sleeve adapted to be engaged by the collar toward the end of the upward movement of the 50 spindle to lift the hopper off of the casing.

3. In a device of the class described, the combination with a frame work having a casing support thereon provided with an elongated bearing collar at the lower end 55 thereof, of a screw threaded packer spindle journaled in said frame work, a packer having an annular surface adapted to coöperate with and extend below the top of the annular bearing surface, an elongated bearing sleeve surrounding the spindle and having a hopper secured on the lower end thereof, vertically disposed bearings in which 60 said sleeve can slide, a stationary nut with

which the threaded packer spindle coöperates, oppositely disposed beveled gears having hollow hubs through which the packer spindle extends, clutch mechanism mounted to slide on the packer spindle and coöperating with the beveled gear wheels, means for rotating the beveled gear wheels, and automatic stop mechanism for shifting the clutch mechanism toward the end of the upward and downward movement of the packer spindle.

4. In a device of the class described, the combination with a frame work having a casing support thereon provided with an elongated bearing collar at the lower end thereof, of a screw threaded packer spindle journaled in said frame work, a packer having an annular surface adapted to coöperate with and extend below the top of the annular bearing surface, an elongated bearing sleeve surrounding the spindle and having a hopper secured on the lower end thereof, vertically disposed bearings in which 70 said sleeve can slide, a stationary nut with which the threaded packer spindle coöperates, oppositely disposed beveled gears having hollow hubs through which the packer 75 spindle extends, clutch mechanism mounted to slide on the packer spindle and coöperating with the beveled gear wheels, means for rotating the beveled gear wheels, and lost motion connections between the packer spindle and the bearing sleeve serving to lift the sleeve automatically toward the end of the upward movement of the packer shaft.

5. In a device of the class described, the combination with a framework adapted to support a casing at a fixed point thereon, of a packer spindle journaled in said framework, a drive shaft, gearing between the drive shaft and packer spindle for rotating the latter from the former in one relative direction at a fixed relative speed and simultaneously moving it toward the casing, a second gearing between the drive shaft and packer spindle for rotating the latter from the former in the other relative direction 105 at a slower relative speed and simultaneously moving it away from the casing, automatic means for disengaging the operative gearing at the end of the longitudinal movement of the spindle in either direction, 110 and hand-operated means for engaging the other gearing after either gearing has been automatically disengaged.

In witness whereof, I have hereunto set my hand and affixed my seal, this 20th day 120 of September, A. D. 1911.

GEORGE WEISS. [L. S.]
